Fig. 6

Fig. 7

FIG. 1 is a top plan view of a playground unit showing my new design;

FIG. 2 is a side elevational view looking diagonally upward toward the right as viewed in FIG. 1;

FIG. 3 is a side elevational view looking diagonally downward toward the right as viewed in FIG. 1;

FIG. 4 is a side elevational view looking diagonally downward toward the left as viewed in FIG. 1;

FIG. 5 is a side elevational view looking diagonally upward toward the left as viewed in FIG. 1;

FIGS. 6 and 7 are side elevational views of the center tower that forms part of the playground unit as seen looking in the direction of lines 6—6 and 7—7, respectively, in FIG. 1; and

FIG. 8 is a top plan view of the playground unit wherein a deck station shown in FIGS. 1, 2, 3 and 5 has

been substituted for the spiral slide shown in FIGS. 1, 3, 4 and 5.

I claim:

The ornamental design for a playground unit, substantially as shown and described.
